Primary Examiner — Darlington Ly(74) *Attorney, Agent, or Firm* — Steven McMahon Zeller;
Dykema Gossett PLLC(57) **CLAIM**

The ornamental design for a fastening clip for cables, as shown and described.

DESCRIPTION

1. Fastening clip for cables

1.1 is a front perspective view of a fastening clip for cables showing our new design;

1.2 is a bottom and rear perspective view thereof;

1.3 is a top and rear perspective view thereof;

1.4 is a top perspective view thereof;

1.5 is a top and front perspective view thereof; and

1.6 is a bottom perspective view thereof.
